(57) **CLAIM**

The ornamental design for a tooth device for use with powered diggers, as shown and described.

DESCRIPTION

FIG. 1 is a perspective view of a tooth device for use with powered diggers, showing my new design;

FIG. 2 is a top plan view of a second embodiment thereof;

FIG. 3 is a right side elevation view thereof;

FIG. 4 is a bottom plan view thereof;

FIG. 5 is a rear elevational view thereof;

FIG. 6 is a front elevational view thereof;

FIG. 7 is a top plan view of a third embodiment thereof;

FIG. 8 is a right side elevational view thereof; and,

FIG. 9 is a top plan view of the first embodiment thereof.
